(57) **CLAIM**

The ornamental design for a front side cowl for motorcycle as shown and described.

DESCRIPTION

FIG. 1 is a front and right perspective view of a front side cowl for motorcycle, showing our new design;

FIG. 2 is a front and left perspective view thereof;

FIG. 3 is a front elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a reference view showing use thereof.

The broken lines shown in the drawings illustrate portions of the front side cowl for motorcycle that form no part of the claimed design.
